UNITED STATES PATENT OFFICE.

WILLIAM BURLINGHAM, OF NEWPORT NEWS, VIRGINIA, ASSIGNOR, BY DIRECT AND MESNE ASSIGNMENTS, TO ENGINEERING PRODUCTS CORPORATION, OF NEWPORT NEWS, VIRGINIA, A CORPORATION OF VIRGINIA.

PNEUMATIC IMPACT-TOOL.

1,357,312.

Specification of Letters Patent.

Patented Nov. 2, 1920.

Application filed February 16, 1915. Serial No. 8,681.

To all whom it may concern:

Be it known that I, WILLIAM BURLINGHAM, a citizen of the United States, residing at Newport News, county of Warwick, 5 State of Virginia, have invented a new and useful Pneumatic Impact-Tool, of which the following is a specification.

In large industrial plants, such as shipyards, boiler works, stone dressing plants 10 and the like, where large numbers of pneumatic hammers are constantly employed for riveting, chipping, calking, dressing stone and analogous uses, the problem of economically furnishing, keeping up or increasing 15 the compressed air equipment for the operation of said tools has become an important economical item in shop management, and the object of my invention is to provide a novel construction of pneumatic tool having 20 a novel fluid distribution system therein, controlled by a single valve, which operates in conjunction with a receiver through a novel arrangement of ports and passages, so that I am enabled to utilize to a maximum 25 extent the expansive effect of the compressed air or other motive fluid which is initially used at high pressure, and I am enabled further simultaneously to employ high pressure live air and low pressure air 30 to augment the velocity or momentum of the hammering plunger prior to or during the act of striking its blow directly upon the shank of the working tool.

Formerly, when comparatively few pneumatic implements were used in large plants, 35 as even now in smaller shops where only a few such tools are employed, the question of the quantity of the cubic volume of air used was given but little consideration, as 40 a small or medium-sized air compressing plant supplying a sufficient amount of air under a given pressure could usually be erected with a reasonable outlay and without occupying an extensive area. Consequently, when the number of pneumatic 45 tools employed was small and the quantity of air consumed by them was relatively small, such consumption of air was more or less ignored so long as the results in 50 power of the tools was obtained.

At the present time, however, in large industrial plants where pneumatic tools and other pneumatic appliances are extensively and continuously used, the size and

initial expense of the air compressors and 55 the space occupied by them, as well as the power and fuel required for their daily operation and the incident cost of their installation, operation and maintenance, have assumed proportions of such magnitude as 60 to require careful attention, and have become of sufficient importance to require the careful consideration of remedies to reduce unnecessary expense, and it is with the object of attaining very much greater efficiency from a volume of air at a given pressure in a pneumatic impact tool wherein the hammering piston impacts directly upon the shank of the working tool for riveting, 65 chipping, calking, dressing stone or analogous uses that my novel single valve tool 70 is designed.

To the above ends, my present invention consists of a novel construction of a fluid distribution system controlled by a single 75 valve for portable, pneumatic impact or hammering tools of that class wherein the forward end of the cylinder is open for the insertion of the shank of the working tool, and wherein the reciprocating piston 80 or plunger preferably hammers directly or indirectly upon said shank, said plunger being actuated by air or other fluid, and my novel construction of tool being adapted for employment particularly in work such 85 as riveting, chipping, calking, hammering and all similar operations wherein the use of a hammer or mallet and chisel has heretofore been employed.

In carrying out the broad principle of 90 my present invention, I apply my motive fluid distribution system to a pneumatic hammer preferably of such size as to be portable and manually held or controlled by the hand of the user, the forward end 95 of the tool cylinder being preferably adapted to be normally open and to have the shank of the chisel, button set or other working tool inserted therein, while my novel construction of reciprocating plunger 100 which I employ is adapted to hammer directly on said shank.

In carrying out my invention, I employ a novel construction of pneumatic tool cylinder and its adjuncts having a barrel provided with bores of different diameters whereby a high pressure cylinder and a low pressure cylinder are formed, in conjunc-

tion with which I employ a novel construction of single valve which serves not only as a high pressure inlet controlling valve, but also as a low pressure exhaust controlling valve, all in conjunction with a receiver common to said valve and its adjuncts and to said high pressure and low pressure cylinders, the foregoing elements being collocated with my novel construction of tool cylinder, which is preferably provided with a grasping handle and a throttling valve mechanism of suitable construction at its rear end, the forward end of said tool cylinder being preferably open for the insertion of the shank of the chisel, button set or other working tool.

As a result of this collocation of my novel construction of high pressure inlet controlling and low pressure exhaust controlling single valve, in combination with a receiver and my novel construction of high pressure and low pressure cylinders and hammering piston, provided with a small diameter and a large diameter portion which at its forward stroke has the function of a tandem piston and in its return stroke has the function of a differential piston, I am enabled to effect a very large saving over the expense in operation of pneumatic tools now in use, and to utilize to a great extent the expansive effect of the compressed air or other motive fluid which is initially used at high pressure, and, as stated, I further simultaneously employ high pressure live air and low pressure air to augment the velocity or momentum of the hammering plunger prior to or during the act of striking its blow upon the shank of the working tool, my novel piston or plunger in its outward stroke having the function of a tandem piston, the piston being so designed that on its return stroke it has the function of a differential piston and is returned toward the tool handle by the preponderance of pressure upon the greater area.

To the above ends, my invention therefore consists in its broad aspects of a novel fluid distribution system for pneumatic hammers, controlled by a single valve, wherein I utilize to a greater extent than heretofore, the expansive properties of the compressed air employed to effect the reciprocations of the hammering piston.

My invention further consists of a novel percussion or impact tool wherein the compressed air is controlled by a single valve and is used expansively in a novel manner in conjunction with my novel valve, so that my novel construction of hammering piston acting as a tandem piston on its forward stroke, is impelled directly on the shank of the working tool during its striking blow by the high pressure live air and by low pressure air simultaneously applied thereto.

It further consists of a pneumatic hammer

comprising my novel construction of single distributing valve in conjunction with a hammering piston having differential piston areas, whereby said piston is returned from the shank of the working tool toward the handle by reason of the preponderance of low pressure motive fluid upon the large differential area of the piston.

It further consists of such a tool having the characteristics above referred to, wherein a single valve is employed, whereby the high pressure live air is substantially only used for initially impelling the tandem or differential hammering piston toward the working tool.

It further consists of an improved arrangement of the operative parts of a pneumatic impact tool whereby the employment of a single valve controlling my novel fluid distribution system enables me to reduce the length of the tool as compared with other tools of similar power, the weight of the tool proportionate to its power being also greatly reduced, which is a very desirable feature in mechanisms of this general character.

It further consists of a novel construction of grasping handle having a chamber formed therein for the reception of a single valve controlling my novel fluid distribution system common to said valve and the coating ports and passages in the barrel of the tool.

It further consists in the novel combination of a grasping handle comprising a throttle valve for controlling the initial admission of motive fluid to the tool, said handle also containing a novel construction of valve chamber and single valve for controlling my novel fluid distribution system.

It further consists of a novel construction of a barrel having passages therein serving as a receiver in conjunction with a novel construction of grasping handle having a single valve therein controlling the fluid distribution system, whereby the reciprocations of the hammering piston are effected.

It further consists of a novel construction of valve and its adjuncts.

It further consists of other novel features of construction, as will be hereinafter pointed out in the claims.

For the purpose of illustrating my invention, I have shown in the accompanying drawings, certain forms thereof which are at present preferred by me, since the same will give in practice satisfactory and reliable results, although it is to be understood that the various instrumentalities of which my invention consists can be variously arranged and organized and that my invention is not limited to the precise arrangement and organization of these instrumentalities as herein shown and described.

Figure 1 represents a longitudinal sec-

tional view of a compound single valve pneumatic hammer, embodying my invention.

Fig. 2 represents a plan view of Fig. 1.

5 Fig. 3 represents a longitudinal sectional view of the barrel or cylinder showing the exhaust port from the forward end of the cylinder in advance of the piston together with the ports for operating the valve.

10 Fig. 4 represents a longitudinal section of the cylinder showing the port connecting the high pressure cylinder through the valve to the forward cylinder in advance of the piston.

15 Fig. 5 represents an end view of the cylinder or barrel, which abuts against the handle.

Fig. 6 represents a transverse section on line $x-x$ Fig. 1, with valve removed.

20 Fig. 7 represents a longitudinal sectional view of the single valve employed.

Fig. 8 represents an inverted plan view of the closure for the valve chamber, showing the exhaust ports therein.

25 Fig. 9 represents a section on line $y-y$, Fig. 8, showing the cylinder for the valve actuating plunger.

Fig. 10 represents a perspective view of the valve actuating plunger employed in 30 conjunction with the valve seen in Fig. 7.

Fig. 11 represents a diagrammatic view showing the cycle of operation and relative arrangement of ports and passages employed in conjunction with my novel single valve, 35 showing the piston at the beginning of its downward stroke and the valve positioned to admit air to both cylinders.

Fig. 12 represents a diagrammatic view similar to Fig. 11 but showing the piston in 40 the act of striking a blow and the valve positioned to permit exhaust from the low pressure cylinder to the atmosphere and admitting air from the high pressure cylinder to the cylinder in advance of the low pressure piston for returning the piston to the position seen in Fig. 11.

Fig. 13 represents a side elevation partly in section showing my novel single valve and compound cylinders as adapted to an 50 open handled tool.

Similar numerals of reference indicate corresponding parts in the figures.

Referring to the drawings,

1 designates my novel construction of 55 compound single valve pneumatic tool, the same comprising a barrel 2 and a handle member 3, which may be of the closed type as shown in Fig. 1, or of the open type, as shown in Fig. 13. The barrel 2 is provided 60 with cylinders of different bores 4 and 5 whereby a high pressure cylinder 4 and a low pressure cylinder 5 are formed. In the forward end of the barrel I locate the tool shank bush 6 having the flanged nut 7, 65 whereby said bush can be screwed into said

barrel, as seen at 8, said bush being locked in position by the engagement of the pin 9 with the hole 10, said pin being held in position by the spring 11 which abuts against the plunger 12, carrying said pin. 13 designates my novel tandem piston, the same comprising the small diameter portion 14 which reciprocates in the high pressure cylinder 4, while the large diameter portion 15 reciprocates in the low pressure cylinder 5, 75 said piston carrying the striking portion 16.

17 designates my novel construction of single valve controlling the distribution of the motive fluid in the compound cylinders 4 and 5, the same comprising a body portion 80 preferably made hollow and having the closed end 18, and the open end 19, and provided with the annular grooves 20 and 21, whereby the distribution of the motive fluid for the operation of the hammer is 85 effected.

22, 23 and 24 designate valve rings, the circumferential edges of which control the admission and exhaust of the motive fluid for the operation of the hammer. In the 90 open end of the valve, I provide a chamber 25 having a seat or shoulder 26 for the reception of the flange 27 of the plunger 28, which is guided in the chamber 29 of the extension 30 of the closure 31, whose construction will be understood from Figs. 1, 8 and 9, said closure having the threaded head 32, through which extend the exhaust ports 33, which in the present instance are four in number, said head being also provided with the annular groove 34 therein, which has the ports 35 communicating therewith, which supply a constant fluid pressure from the main supply 36 to the chamber 29 above the valve actuating plunger 28 by 105 means of the port 37 and passages 38 and 39.

40 designates a valve lining which I preferably employ and which is provided with ports coacting with the valve, as will be explained, said valve and lining being in the 110 present instance located in that portion of the handle nearest the barrel, although it will be evident that the valve and its adjuncts might be located in any other desirable position or portion of the tool. It will 115 also be evident that my novel valve mechanism may be employed in conjunction with a handle 3 of the closed type, as seen in Fig. 1, or it may be employed with an open handle 41 of the type seen in Fig. 13. In both types 120 of said handles the pressure supply duct is indicated at 36, and the flow of the motive fluid is controlled by the manually operated or controlled throttle valve 42, commonly employed in handles of this general character.

The handle socket 43 may be secured to the barrel 2 by any desired means but I preferably employ the construction seen in Fig. 1, wherein I have shown said socket in 130

4
threaded engagement with said barrel, the parts being locked in assembled position by the engagement of the pin 44 with the hole 72, said pin being held in the desired position by the tension of the spring 45 on the pin plunger 46. In the rear end of the barrel 2, I locate the receiver 47, which consists of a plurality of longitudinally extending chambers, in the present instance five in number, as seen in Fig. 5, connected together, in the present instance, by slots 48, as seen in Figs. 1 and 5, thus forming one common receiver chamber.

10 The cycle of my novel motive fluid distribution system which occurs during the reciprocal movements of my coacting motive fluid distributing valve and hammering piston will now be explained and will be clearly understood from the foregoing description and the following reference to the diagrammatic views seen in Figs. 11 and 12.

15 Referring first to Fig. 11, the hammering piston 13 is shown in position to begin its outward stroke toward the shank of the working tool, and the valve 17 is shown in such extreme position as to admit air to both cylinders and to permit exhaust to the atmosphere through the ports 33 from the cylinder in advance of the low pressure piston. Upon opening the throttle 42, the motive fluid enters the main supply duct 36, and passes thence through passages 37, 38, 39, groove 34, and passages 35 to the top of the chamber 29, back of the end of the plunger 28, which moves the valve 17 into the position seen in Figs. 1 and 11. The live air now passes through the passage 49, and the port 50 into the annular groove 20 of the valve 17, and flows through the port 51, the passage 52 and port 53 to the end of the high pressure cylinder 4 and forces the piston toward the shank of the working tool. The exhaust from the cylinder in advance of the low pressure piston passes through port 54, passage 55 and port 56 into the chamber 57 at the end of the valve and thence to the atmosphere through the passages 33. During this first stroke of the piston the receiver 47 has no pressure therein and therefore the low pressure cylinder 5 has no pressure therein.

20 When the piston has reached the end of its outward stroke, live air in the high pressure cylinder flows through passage 58 to the receiver 47, thus equalizing the pressure in said receiver and high pressure cylinder. At the same time the live air passes from the high pressure cylinder 4 through the passages 59 and 60 to the closed end 18 of the valve 17, forcing the latter from the position seen in Fig. 11 to the position seen in Fig. 12, the piston 13 being also now in the position seen in Fig. 12.

25 Referring to Fig. 12, the hammering pis-

ton 13 is shown in position to begin its inward stroke away from the shank of the working tool and valve 17 is shown in such other extreme position as to exhaust the air from the low pressure cylinder 5 through the passage 70, port 69, annular groove 21 and port 71 to the atmosphere. At the same time, the air from the high pressure cylinder 4 exhausts through passages 53, 52, port 51, annular groove 20 of the valve 17, port 61, passage 62 and port 63 to the cylinder 75 in advance of the low pressure piston, thereby equalizing the pressure in the high pressure cylinder and the cylinder forward of the low pressure piston 15.

30 By reason of the differential areas of the pistons 14 and 15, the preponderance of pressure upon the larger forward area causes the piston to move inwardly or away from the shank of the working tool, said piston now being in the position seen in Fig. 11. When the piston has returned to the position seen in Fig. 11, the annular groove 64 therein registers with passages 65 and 66, thus allowing the air pocketed back of the closed end 18 of the valve 17 to exhaust through passages 60 and 65, annular groove 64 and passage 66 to the atmosphere. The opening of the exhaust passages last described, causes a reduction of the pressure on the closed end 18 of the valve 17 whereupon the preponderance of the pressure upon the opposite end of the valve due to the pressure upon the plunger 28 through the medium of the port and passages communicating with the chamber 29, causes said valve to assume the position seen in Fig. 11. The foregoing description is definitive of the first outward and inward stroke of the hammering piston and the first complete travel of the valve to and fro, these movements coacting in such a manner as to permit the correct distribution of the motive fluid. The receiver 47 was filled with air, at the end of the first outward stroke of the piston 13, through the passage 58. On the second outward stroke and all succeeding strokes, the air from the receiver 47 flows through passage 67 and port 68, annular groove 21, port 69 and passage 70 to the low pressure cylinder. It will thus be seen that while the energy of the first outward stroke of the hammering piston is due solely to live air pressure on the high pressure piston, this energy on the second and all succeeding outward strokes of said piston is augmented by the energy due to the air from the receiver acting on the low pressure piston. The cycle of the air distribution in the second and succeeding outward strokes of the piston is the same as that of the first outward stroke with the exception that the air from the receiver is admitted

through the passages heretofore described to the low pressure piston.

It will be apparent from the foregoing that high pressure air and low pressure air 5 simultaneously coöperate to augment the operative outward stroke of the hammering piston, the latter in its outward movement toward the shank of the working tool having the function of a tandem piston. Low 10 pressure air only is employed to return the piston from the shank of the hammering tool, said return being effected by the preponderance of pressure upon the large or forward area of the hammering piston. The 15 only exhaust is of low pressure air, which has performed its functions directly and expansively. After the high pressure air has forced the piston down or outwardly to deliver the blow upon the shank of the 20 working tool, a part of the expanding air is directly employed to return the piston, the piston on its return movement having the function of a differential piston while a part of said expanding air is stored away 25 in the receiver 47 to be employed to act against the low pressure piston of the plunger in the driving stroke of the latter. As stated, no air being exhausted excepting 30 low pressure air which has been used in the low pressure cylinder and in the valve chamber, a very high efficiency is obtained by using the air at its original pressure and thereupon again by compound use of the expanded air exhausted from the high 35 pressure cylinder.

By forming the receiver member 47 from longitudinal bores in the barrel 2 of the tool and connecting them by the ports or passages 48, such receiver does not add to the 40 length or weight of the tool, and the existence of the bores or passages forming the receiver 47 will materially reduce the weight of the tool by cutting away otherwise useless material.

45 By the employment of the single valve in the body portion of the grasping handle and making such valve hollow and arranging the valve preferably transversely to the barrel, the over-all length of the tool is also reduced 50 and the weight of the handle is considerably diminished. As the hammering piston is returned by the expanded live air acting against differential piston areas, the return or upstroke of the hammering piston is 55 cushioned and the shock and vibration of the tool are considerably reduced, thereby easing the hold of the tool to the work.

I have found by careful experiments and calculation, that my novel construction of 60 hammer will, in addition to striking a harder blow, reduce the air consumption very greatly below the consumption of similar tools. While the outward stroke of the hammering piston is performed on the

compound principle, employing live air and 65 partly expanded air, or, in other words, is effected by the action of high pressure and low pressure motive fluid combined, the compound principle is not employed for the 70 return stroke, which is performed by the differential action of the expanded or low pressure fluid.

It will further be seen that by making my 75 novel construction of single valve hollow and providing the same with the heads or pistons 22, 23 and 24 of the same diameter, the same can be readily manufactured and ground, and the valve lining or casing can be also readily and cheaply manufactured.

By the employment of my hammering 80 piston in conjunction with the high and low pressure cylinders having my novel fluid distribution system controlled by a single valve, it will be seen that I provide an efficient means for equalizing the air pressure 85 in the high pressure cylinder and the low pressure cylinder between the striking end of the differential piston and the shank of the working tool, thereby utilizing the air in the high pressure cylinder after the receiver has been filled to return the hammering 90 piston.

I desire to call special attention to the 95 fact that my invention in its broad aspects is especially applicable to that type of light or portable, manually held impact tools especially adapted for riveting, chipping, calking, hammering or analogous uses, wherein the forward end of the barrel is open for the insertion of the shank of the working 100 tool, and wherein the hammering piston impacts preferably directly upon said shank of the rivet set, chisel or other working tool.

My present invention is differentiated 105 from my Patent No. 1,123,678, granted January 5, 1915, wherein I have shown two distribution valves employed and have shown the receiver as located in an extension of the grasping handle, and while tools embodying the subject-matter of my prior 110 patent aforesaid have been found to be practicable and therefore commercially successful and to effect a saving of a very large per cent. in the air consumption over similar tools in use, I prefer for some reasons to 115 employ my present construction of pneumatic tool, since by the employment of a single valve, I am enabled to reduce the number of moving parts and to also simplify and lighten the tool structure.

120 My present tool, in addition to possessing all the advantages of my prior patent hereinabove referred to, possesses the additional advantages of having fewer moving parts, and has been found by calculation to be 125 somewhat lighter and even more efficient than the tools constructed under my prior patent aforesaid.

Generally speaking, among the advantages of my present invention over my prior patent aforesaid, as well as other prior devices, are:—

- 5 1st. Decrease in weight;
- 2nd. Decrease in cost of manufacture;
- 3rd. Decrease in the number of moving parts;
- 4th. Decrease in the friction of the air by reason of shorter passages;
- 10 5th. Decrease in liability of getting out of order by reason of the small number of parts;
- 6th. It can be assembled and disassembled 15 quicker; and
- 7th. Decrease in diameter of the high pressure cylinder, thus making it possible to use a lighter piston, with consequent advantages in effectiveness.
- 20 In the hammer of my prior patent aforesaid, I designed the same so as to cut off the air supply at about the middle of the stroke in the high pressure and low pressure cylinders which necessitated the preferable em- 25 ployment of two valves, one to operate to cut off the air supply to the high pressure and low pressure cylinders, and the other to open these cylinders to exhaust at the end of the stroke.
- 30 In order to employ the broad principle of my invention aforesaid in a tool having a single valve, I therefore reduce the diameter of the high pressure cylinder in such pro- 35 portion as to supply the same work in the high pressure cylinder taking air the full stroke as was formerly taken in the high pressure cylinder of my prior tool to the point of cut off. The pressure in the high pressure cylinder of my present invention 40 employing a single valve at the end of the stroke is equal to the initial pressure, and the air in the receiver expands only in both the receiver and low pressure cylinders during the entire stroke. By this arrangement, 45 the times of cut off and exhaust are made substantially simultaneous and the use of a single valve is made possible and practical and commercially successful.

I am aware that it has heretofore been proposed to use compressed air somewhat as in a compound engine in rock drills or similar structures, which employ massive and heavy reciprocating engines frequently weighing several hundred pounds, and 55 which are required to be supported upon a suitable tripod, and wherein the drill or other working tool is connected to or reciprocates directly in unison with the reciprocating piston. My present invention is, 60 however, clearly differentiated from massive tools of this character having a comparatively slow moving piston, for the reason that my present device is particularly applicable to the small, manually held and man- 65 ually controlled riveters or chipping tools,

wherein the tool is usually supported in the hands of the operator only, and wherein the hammering piston reciprocates with great rapidity and impacts directly upon the shank of the chisel, rivet set or other working tool.

My present invention is further differentiated from the compound rock drills having the comparatively slow moving piston aforesaid or the ordinary compound engine 75 in the matter of the motor fluid distribution, for the following reasons:—

In a compound engine, the expanded fluid of the high pressure cylinders after the stroke has been completed exhausts in its 80 entirety into the receiver during practically all of the return stroke, while in my present invention, the cycle of the motor fluid distribution is quite different, since I employ but a single valve, and I take a part of the 85 expanded air of the high pressure cylinder to the receiver, and from this receiver the air is taken for the upper end of the low pressure cylinder to drive the piston against the shank of the working tool on its working 90 stroke. The remainder of the expanded air left in the high pressure cylinder after the receiver is filled is used to return the differential plunger by a differential or pre-ponderance of pressure upon the small and 95 large piston areas, the pressure of this expanded air in the high pressure cylinder and the pressure in the chamber in advance of the low pressure cylinder on the forward end of the piston being equalized through a connecting passage.

By the employment of the live air and partly expanded air upon the hammering piston during the period it is striking the blow, wherein it is having the function of a tandem piston, the velocity and momentum of the reciprocating plunger are greatly augmented during the period when such increase of power is desirable, and by the employment of the differential action of the 105 expanded and low pressure fluid to return the hammering piston after its impact against the shank of the working tool, the expansive action of the motive fluid is utilized to the greatest possible extent, as will 110 be apparent to those skilled in the art.

It will further be apparent in my invention, that by the employment of the receiver and its adjuncts, the extensive vibration heretofore incident to the operation of tools 115 of this character, particularly during riveting and chipping, is eliminated to a great extent.

So far as I am aware, I am the first in the art to employ in a pneumatic tool of the 120 character heretofore described, a single valve controlling the cycle of motor fluid distribution.

I am also the first in the art to employ a handle member having therein a single 125

valve controlling the distribution of the motor fluid in the manner heretofore described.

I am also the first in the art to employ a handle member having a single valve therein in conjunction with a barrel having a receiver and the hereinbefore described collocation of ports and passages.

I am also the first in the art to employ a handle member having therein a single valve controlling the motor fluid distribution system hereinbefore described when combined with a barrel having a high pressure cylinder, a low pressure cylinder, and a receiver therein, said cylinders being provided with a plunger of the character described.

I am also the first in the art to employ in a portable, manually held pneumatic hammer having a barrel provided with its front end open to receive the shank of the working tool, the features of a hammering piston acting as a tandem piston in its forward stroke, and a differential piston in its rearward stroke, combined with a single controlling valve and a receiver, whereby motive fluid may be used expansively as described, and my claims to these features are therefore to be interpreted with the corresponding scope awarded to a pioneer invention.

I am also the first in the art to employ a tandem hammering piston having two varying areas in line with each other, the working pressure to drive the piston forward and strike its blow upon the working tool acting on the same side of each piston simultaneously, said piston being returned by the preponderance of pressure upon its larger area, in conjunction with a single valve of any character whatsoever.

I am also the first to employ a single valve in compounding the air into two or more cylinders.

It will now be apparent that I have devised a new and useful pneumatic impact tool embodying the features of advantage enumerated as desirable in the statement of the invention and the above description, and while I have shown and described certain forms thereof which will give in practice satisfactory and reliable results, it is to be understood that the same is susceptible of modification in various particulars without departing from the spirit or scope of the invention or sacrificing any of its advantages.

Having thus described my invention, what I claim as new and desire to secure by Letters Patent, is:—

1. In a compound pneumatic impact tool, a barrel, a small diameter cylinder therein, a large diameter cylinder, a small diameter and large diameter piston adapted to reciprocate in said cylinder, a single valve for

controlling the distribution of motive fluid, and means coacting with said single valve to utilize the energy left in the air after it has been initially used in one cylinder, for the purpose of augmenting the energy of 70 said piston.

2. In a compound pneumatic impact tool, a barrel, a large diameter cylinder therein, a small diameter cylinder, a large diameter piston and a small diameter piston fitting 75 said cylinders, the sum of the pressure on the rear working faces of the piston causing the striking blow, and the difference of pressure on the opposite extremities of said piston effecting the return of said piston, 80 and a single valve controlling the air distribution to and from said cylinders, in combination with means coacting with said single valve to utilize the energy left in the air after it has been initially used in one cylinder 85 for augmenting the energy of said piston.

3. In a compound pneumatic impact tool, a barrel having its forward end open to receive the shank of the working tool, and 90 provided with cylinders of different diameters, a piston of varying diameter conforming to said cylinders, a receiver, and a single valve effecting the entire distribution of motive fluid to and from said cylinders, in combination with means coacting with said single valve to utilize the energy left in the air after it has been initially used in one cylinder 95 for augmenting the energy of said piston.

4. In a pneumatic impact tool, a barrel, cylinders therein, a piston in said cylinders, a receiver formed in said barrel exteriorly to said cylinders, and a single valve for controlling the flow of the motive fluid to and 100 from said cylinders and into and from said receiver.

5. In a pneumatic impact tool, a barrel, cylinders therein, a piston in said cylinders, a receiver formed in said barrel, and a single valve for controlling the flow of the motive fluid to and from said cylinders and into and from said receiver, said single valve being operated in one direction by the motive fluid at substantially the receiver 110 pressure, in combination with means coacting with said single valve to utilize the energy left in the air after it has been initially used in one cylinder for augmenting the energy of said piston.

6. In a pneumatic impact tool, a barrel, cylinders therein, a piston in said cylinders, a receiver formed in said barrel, and a single valve for controlling the flow of the motive fluid to and from said cylinders and into and from said receiver, said valve being operated in one direction by the motive fluid at substantially the receiver pressure, and in the opposite direction by constant live air pressure.

7. In a pneumatic impact tool, a small diameter cylinder, a large diameter cylinder, a small diameter and large diameter piston adapted to reciprocate in said cylinders, a receiver connected to receive expanded motive fluid from the small diameter cylinder, and a single valve adapted to control the flow of live motive fluid to said small diameter cylinder and expanded motive fluid from said large diameter cylinder.

8. In a pneumatic impact tool, a plurality of cylinders of different diameters, pistons of different diameters fitted to reciprocate in said cylinders, a receiver connected to receive expanded motive fluid from a small diameter cylinder, passages adapted to connect said receiver with an end of said large diameter cylinder, and a single valve adapted to control the flow of live motive fluid to said small diameter cylinder.

9. In a pneumatic impact tool, a small diameter cylinder and a large diameter cylinder, a plunger having a small diameter and a large diameter piston reciprocable in said cylinders, a receiver connected to receive expanded motive fluid from the small diameter cylinder, a single valve, a passage controlled by said valve to admit expanded motive fluid from the receiver to the upper or inner face of the large diameter piston, and a passage to simultaneously admit live motive fluid to the upper or inner face of the small diameter piston, in combination with means coacting with said single valve to utilize the energy left in the air after it has been initially used in one cylinder for augmenting the energy of said piston.

10. In a pneumatic impact tool, a small diameter and a large diameter cylinder portion, a plunger having a small diameter and a large diameter piston respectively reciprocable in said cylinder portions, a receiver having a passage leading to it from the forward portion of the small diameter cylinder, and a single valve controlling the flow of live motive fluid to the inner end of the small diameter cylinder, and expanded motive fluid from the receiver to the inner face of the large diameter piston.

11. In a pneumatic impact tool, a barrel, a small diameter high-pressure cylinder, a large diameter low-pressure cylinder, a piston having small diameter and large diameter portions respectively reciprocable in said cylinders, a receiver, and a single valve connected to intermittently admit live motive fluid at the inner end of the high-pressure cylinder and to intermittently admit expanded motive fluid from said receiver to an end of said low-pressure cylinder to drive said piston outwardly, said valve having constant fluid pressure on an end thereof.

12. In a pneumatic impact tool, a barrel, small diameter and large diameter cylinders

therein, a piston having small and large diameter portions respectively reciprocable in said cylinders, a receiver in said barrel connected to the outer portion of the small diameter cylinder to receive expanded motive fluid from the latter, a valve chamber connected to the forward ends of the large diameter cylinder and to the inner end of the small diameter cylinder, and a single valve in said valve chamber adapted to control the distribution of motive fluid to said small cylinder and expanded motive fluid from the small diameter cylinder to the large diameter cylinder.

13. In a pneumatic impact tool, a barrel, small diameter and large diameter cylinders therein, a piston having small and large diameter portions respectively reciprocable in said cylinders, a receiver in said barrel connected to the outer portion of said small diameter cylinder to receive expanded motive fluid from the same, a single valve chamber connected to the inner and outer ends of said large cylinder, and a single valve reciprocable in said chamber to intermittently admit motive fluid at the inner end of said small diameter cylinder and to intermittently connect the inner end of said large diameter cylinder to exhaust.

14. In a pneumatic impact tool, a barrel, small diameter and large diameter cylinders therein, a piston having small and large diameter portions respectively reciprocable in said cylinders, a receiver in said barrel having a passage to it from the outer portion of said small diameter cylinder, a single valve chamber having an inlet for the motive fluid and ports connected to the inner ends of said cylinders and an exhaust, and a single valve in said valve chamber adapted to admit motive fluid to the small diameter piston and expanded motive fluid from the receiver to the inner portion of the large diameter piston and intermittently connect the inner end of the large diameter cylinder to an exhaust, said valve being actuated in one direction by constant pressure, and in the opposite direction by motive fluid which has driven said piston outwardly.

15. In a pneumatic impact tool, a barrel having its forward end open to receive the shank of the working tool, and having cylinders of different diameters, a piston having portions of different diameters to reciprocate in said cylinders, a receiver, and a single valve by which the live motive fluid can be admitted simultaneously to each cylinder, and also exhausted simultaneously from each cylinder.

16. In a pneumatic impact tool, a barrel, high pressure and low pressure cylinders therein, a grooved piston located in said cylinders, a valve chamber, a receiver in said barrel, and a single valve in said chamber controlling ports common to said cylinders,

valve chamber and receiver, said valve being actuated in one direction by constant live air pressure upon one end thereof, and intermittent live air pressure upon the other end 5 thereof, the groove in said piston permitting exhaust from one end of said valve.

17. In a pneumatic impact tool, a barrel, high pressure and low pressure cylinders therein, a grooved piston in said cylinder 10 having a small diameter portion and a large diameter portion, a receiver, a valve chamber and a single distribution differential valve therein controlling ports common to said cylinders, valve chamber and receiver, 15 said piston acting on its outward stroke as a tandem piston and on its inward stroke as a differential piston, said latter movement being effected by a preponderance of pressure on the large area of said piston, and the 20 groove in said piston permitting exhaust from the larger end of said valve.

18. In a pneumatic impact tool, a valve chamber, a single differential valve therein, a plunger coacting with said valve, a hammering piston having a groove therein coacting with the larger end of said valve, means 25 for constantly introducing live air pressure upon an end of said plunger, thereby actuating said valve, means for intermittently introducing pressure on the opposite end of said valve, a barrel for the reception of said hammering piston therein, and a receiver, 30 said barrel, valve chamber and receiver having ports and passages common to each 35 other, and the groove in said piston permitting exhaust from the larger end of said valve when said piston is in its rearmost position.

19. In a compound pneumatic impact tool, 40 a barrel having a high pressure cylinder and a low pressure cylinder therein, a piston therein provided with a groove and having a small diameter portion and a large diameter portion, a receiver, a valve chamber, a 45 single differential valve therein, controlling ports common to said cylinders, valve chamber and receiver, the groove in said plunger permitting exhaust from the larger area of 50 said valve, a plunger coöperating with said valve, a plunger chamber, having live air constantly admitted thereto, and a closure for said plunger chamber, said closure having constantly open exhaust ports therein.

20. In a pneumatic impact tool, a barrel 55 having a high pressure cylinder and a low pressure cylinder therein, a grooved hammering piston therein having a small and large diameter portion, a receiver also located in said barrel, a valve chamber, a 60 single differential valve in said valve chamber, controlling ports common to said cylinders, valve chamber and receiver, a plunger coöperating with said valve, means for exerting constant live air pressure on said 65 plunger and valve in one direction, and

means for exerting an intermittent pressure on the larger area of said valve in the opposite direction, the exhaust from the larger area of said valve being permitted by the groove in said piston, when the latter reaches 70 one of its extreme positions.

21. In a pneumatic impact tool, a barrel having a high pressure cylinder and a low pressure cylinder therein, a piston therein having a small diameter portion and a large 75 diameter portion, a receiver, a valve chamber, a single hollow differential valve therein, controlling ports common to said cylinders, valve chamber and receiver, a plunger having a flange thereon coacting with said 80 valve, means for exerting constant pressure on said valve and plunger in one direction, means for effecting the actuation of said valve in the opposite direction, and means controlled by said piston for permitting exhaust from the larger area of said valve when said piston reaches the extreme of its inner stroke, said piston acting as a tandem piston on its forward stroke and as a differential piston on its inner or return stroke. 85 90

22. In a pneumatic impact tool, a barrel, small diameter and large diameter cylinders therein, a piston having small diameter and large diameter portions respectively reciprocable in said cylinders, a receiver connected 95 to receive expanded motive fluid from the small diameter cylinder, a single, hollow, differential valve, and passages controlled by said valve and connected to admit live motive fluid to the inner end of the small 100 diameter cylinder and expanded motive fluid from the receiver alternately to the inner end of said large diameter cylinder, a closure for said valve chamber, having constantly open ports therein and a plunger 105 chamber, a plunger in said plunger chamber coacting with said valve, means for introducing constant live air pressure on said plunger and valve to move them in one direction, and means for permitting the exhaust from the larger end of said differential valve, when said piston reaches one extreme 110 of its stroke.

23. In a pneumatic impact tool, a barrel having high and low pressure cylinders 115 therein, a grooved hammering piston in said cylinders having small and large diameter portions, a receiver also located in said barrel, a valve chamber, a single differential valve therein, controlling ports common to 120 said cylinders, valve chamber and receiver, a closure for said valve chamber having constantly open exhaust ports therein, a plunger coöperating with said valve and contained in a plunger chamber formed in 125 said closure, means for constantly introducing live air pressure into said plunger chamber to actuate said plunger and valve in one direction, and means for intermittently introducing pressure upon the larger 130

area of said valve to actuate the latter in the opposite direction, the exhaust from said larger area being controlled by the groove in said piston when the latter reaches the 5 extreme of its inner stroke.

24. A distribution valve for a compound pneumatic tool, comprising a body portion having two annular grooves therein, thereby forming three valve rings, said body being 10 closed at one end and open at the other, said open end having a shoulder therein adapted to receive and coact with a plunger operable in unison with said valve.

25. A distribution valve for a compound 15 pneumatic impact tool, comprising a hollow body portion having a plurality of annular grooves therein, thereby forming valve rings, said valve body being closed at one end and open at the other, said open end 20 having a shoulder therein adapted to receive the flange of a coacting plunger.

26. The combination of a valve chamber, a closure therefor, a plunger chamber in said closure, the latter having constantly open 25 exhaust ports therein, a plunger in said chamber, means for admitting constant pressure into said plunger chamber, a valve having one end closed in said valve chamber and coacting with said plunger, means for intermittently admitting and exhausting air to and from said closed end of said valve, a barrel having high and low pressure cylinders therein, and a piston in said cylinders controlled by said valve.

35. 27. The combination of a valve chamber, a closure therefor, a plunger chamber in said closure, the latter having constantly open exhaust ports therein, a plunger in said chamber, means for admitting constant 40 pressure into said plunger chamber, a differential valve in said valve chamber and coacting with said plunger, said valve having one end closed, means for intermittently admitting and exhausting air to and 45 from said closed end of said valve, a barrel having high and low pressure cylinders therein, a receiver, and a piston in said cylinders controlled by said valve.

28. In a compound pneumatic impact tool, 50 a valve chamber, a closure therefor, a plunger chamber in said closure, said closure having constantly open exhaust ports therein, a plunger in said chamber, means for admitting constant pressure into an end of 55 said plunger chamber, a hollow, differential valve in said valve chamber coacting with said plunger and having its end opposite to said plunger closed, means for directing constant pressure on said plunger and one 60 end of said valve, a barrel, a hammering piston therein, and means for intermittently admitting and exhausting air from the closed end of said valve.

29. In a compound pneumatic impact tool, 65 a valve chamber, a closure therefor, a plun-

ger chamber in said closure, said closure having constantly open exhaust ports therein, a plunger in said chamber, means for admitting constant pressure into an end of said plunger chamber, a hollow differential valve 70 in said valve chamber, coacting with said plunger and having its end opposite to said plunger closed, means for directing constant pressure on said plunger and one end of said valve, a barrel, a hammering piston therein, 75 and means for intermittently admitting and exhausting air from the closed end of said valve, in combination with a receiver, and passages common to said receiver, barrel and valve chamber.

30. In a compound pneumatic impact tool, a barrel, a hammering piston therein, a receiver in said barrel, a valve chamber, a single valve in said valve chamber, provided with a plurality of grooves and rings, means 85 for introducing constant pressure on one end of said valve, and means controlled by said piston for permitting intermittent pressure and exhaust upon the opposite end of said valve.

31. In a compound pneumatic impact tool, a barrel, a grooved hammering piston therein, a receiver in said barrel, a valve chamber, a single valve in said valve chamber, provided with a plurality of grooves and rings, 95 means for introducing constant pressure on one end of said valve, and means controlled by said piston for permitting intermittent pressure and exhaust upon the opposite end of said valve.

32. In a compound pneumatic impact tool, a barrel, high and low pressure cylinders therein, a hammering piston having high and low pressure areas thereon, a receiver carried by said barrel, a valve chamber, a single valve therein, provided with a plurality of grooves and rings, means for introducing constant pressure upon one end of said valve, and means for permitting intermittent pressure and exhaust upon the opposite end of said valve.

33. In a compound pneumatic impact tool, high and low pressure cylinders therein, a hammering piston having high and low pressure areas thereon, a receiver carried by said barrel, a valve chamber, a single valve therein provided with a plurality of grooves and rings, a plunger coacting with said valve, means for introducing constant pressure upon one end of said plunger and valve, and means controlled by said piston for permitting intermittent pressure and exhaust upon the opposite end of said valve.

34. In a compound pneumatic impact tool, the combination of a cylinder, a piston therein, a single valve, a receiver, and means for operating said piston by means of the pressure of the expanded air in the receiver.

35. In a compound pneumatic impact tool, a cylinder, a piston therein, a single valve, a 130

receiver, and means for operating said piston by the pressure of the expanded air in said receiver, said valve being actuated in one direction by constant pressure and in 5 the opposite direction by pressure and exhaust passages controlled by said piston.

36. In a compound pneumatic impact tool, a small diameter cylinder, a large diameter cylinder, a small diameter and large diameter 10 piston adapted to reciprocate in said cylinder, a single valve, and means controlled by said single valve for using energy left in the air after it has been used in one cylinder, for augmenting the energy of said piston.
37. In a compound pneumatic impact tool, a small diameter cylinder, a larger diameter cylinder, small diameter and larger diameter pistons adapted to reciprocate in said cylinders, a single valve, and means controlled 15 by said single valve for using the energy left in the motive fluid after it has been used in any of the cylinders for augmenting the blow of said plungers.

38. In a compound pneumatic impact tool 20 having open ends, a plurality of cylinders of varying diameter, pistons of varying diameter adapted to fit said cylinders, a single valve, and means controlled by said single valve for utilizing the remainder of the 25 energy left in the expanded air after it has been exhausted from the initial pressure cylinder to increase the energy of the stroke of the piston without increase of consumption of the free air.

39. In a compound pneumatic impact tool, a small diameter and a large diameter cylinder portion, a small diameter and a large diameter piston respectively reciprocable in 30 said cylinder portions, a receiver, and a single distribution valve, said small diameter cylinder portion having passages near its outer end connected at intervals to said receiver by said piston.

40. In a compound pneumatic impact tool, 35 a small diameter and a large diameter cylinder portion, a small diameter and large diameter piston in said cylinder portions, a receiver, a valve chamber, and a single distribution valve in said chamber, said small 40 diameter cylinder portion having passages near its outer end connected at intervals to said receiver and one end of said valve by said piston, the opposite end of said valve having constant pressure thereon.

41. In a compound pneumatic impact tool, a plurality of working cylinder portions of different diameters, pistons of different diameters reciprocable in said cylinder portions, a single valve, means controlled 45 by said single valve for admitting motive fluid to a small diameter cylinder portion, receivers, means admitting expanded motive fluid from said small diameter cylinder portion to such receiver, and 50 means controlled by said single valve for

admitting expanded motive fluid from said receiver to a large diameter piston.

42. In a pneumatic tool, a small diameter and a large diameter cylinder portion, a large diameter and a small diameter 55 piston, reciprocable in said cylinder portion, a receiver, a single valve, means controlled by said single valve for intermittently admitting motive fluid into the small diameter cylinder portion, means controlled 60 by said piston for alternately admitting the expanded fluid from the small diameter cylinder portion to the receiver, and means controlled by said single valve for equalizing the pressure of the motive fluid remaining 65 in the small diameter cylinder after the receiver has been filled with motive fluid, between the small diameter cylinder and the space in front of the large piston.

43. In a compound pneumatic impact tool, 70 a working cylinder formed with a small diameter portion and a large diameter portion, a small diameter and a large diameter piston slidable in said cylinder portions, a single valve, means controlled by 75 said valve for admitting motive fluid to said small diameter cylinder portion, a receiver, means controlled by said piston for admitting expanded fluid from said small diameter cylinder portion to said receiver, 80 and means connected to coöperate with the motive fluid admitting means to simultaneously admit expanded fluid from said receiver back of the large diameter piston.

44. In a compound pneumatic hammer, 100 a barrel having a differential piston chamber forming high pressure and low pressure cylinders, a plunger therein having high pressure and low pressure piston areas, a receiver, a single distribution valve, means 105 controlled by the latter for simultaneously utilizing live motive fluid on the high pressure area of said plunger and expanded motive fluid from said receiver upon a large area of said plunger to drive said 110 plunger outwardly.

45. In a compound pneumatic impact tool, a small diameter and a large diameter cylinder portion, a large diameter and a small diameter piston reciprocable in said 115 cylinder portions, a single valve, means controlled by said valve for intermittently admitting motive fluid into the small diameter cylinder portion, a receiver, means controlled by said piston for conducting expanded motive fluid exhausted from the small diameter cylinder portion to said receiver, and means controlled by said valve for alternately admitting expanded fluid from said receiver to an end of the large diameter 120 cylinder portion.

46. In a compound pneumatic impact tool, a small diameter and a large diameter cylinder portion, a small diameter and a large diameter piston reciprocable in said 130

- cylinder portions, a single valve for intermittently admitting motive fluid into said small diameter cylinder portion, a receiver, means controlled by said piston for conducting expanded fluid from said cylinder portion to said receiver, means connected to the motive fluid admitting means to simultaneously admit expanded fluid from the receiver to the large diameter cylinder portion 5 back of the piston in the same, and means controlled by said single valve for connecting the opposite ends of the cylinder portions to admit of expanded fluid differentially acting against the pistons.
- 15 47. In a compound pneumatic impact tool, a small diameter and a large diameter cylinder portion, the latter having an opening for the shank of the working tool, a small diameter and a large diameter piston reciprocable in said cylinder portions, passages connected to the opposite ends of said cylinder portions, a receiver, and a single controlling valve arranged to intermittently connect said passages, said single 20 valve also controlling the exhaust from said 25 large diameter piston.
48. In a compound pneumatic impact tool, a small diameter and a large diameter cylinder portion, a small diameter and a large diameter piston reciprocable in said cylinder portions, a receiver, a passage from near the outer end of said small diameter cylinder portion to said receiver, a single valve for intermittently admitting motive 30 fluid to the small diameter cylinder portion, and a passage from said receiver to the inner end of the large diameter cylinder portion, said single valve controlling admission of expanded fluid from said receiver through said passage to said large 35 cylinder portion.
49. In a compound pneumatic impact tool, a small diameter and a large diameter cylinder portion, a small diameter and a large diameter piston reciprocable in said cylinder portions, a receiver, a passage from near the outer end of said small diameter cylinder portion to said receiver, a single valve for intermittently admitting 45 motive fluid to the small diameter cylinder portion, a passage from said receiver to the inner end of the large diameter cylinder portion, said single valve controlling admission of expanded fluid from said receiver through said passage to said cylinder 50 portion, and a passage between the opposite ends of said cylinder portions also controlled by said single valve.
50. In a compound pneumatic impact tool, 60 a small diameter and a large diameter cylinder portion, a small diameter and a large diameter piston reciprocable in said cylinder portions, a single valve for intermittently admitting motive fluid into said small diameter cylinder portion, a receiver, a pas-

sage from near the end of said small diameter cylinder portion to said receiver, a passage connecting said receiver and the upper or inner end of the large diameter cylinder portion, said single valve controlling said 70 passage, the exhaust from said inner end of said large cylinder portion being also controlled by said single valve, and a passage connecting opposite ends of said cylinder portions, also controlled by said single valve. 75

51. In a compound pneumatic tool, a barrel provided with a differential piston chamber having its front end open to receive the shank of the working tool, a differential plunger in said cylinder, a single valve serving as a high pressure inlet controlling valve and as a low pressure exhaust controlling valve, and a receiver coacting with said valve and piston chamber. 80

52. In a pneumatic hammer, a barrel having a differential piston chamber, the forward end of said barrel being open for the reception of the shank of the working tool, a differential plunger in said piston chamber having pistons of different areas, a receiver, and a single controlling valve for admitting air at initial pressure to the high pressure cylinder and at the same time admitting air from the receiver to the inner end of said low pressure cylinder, said valve 95 controlling communication between said receiver and said low pressure piston chamber.

53. In a pneumatic hammer, a barrel having its forward end open for the shank of 100 the working tool and provided with a differential piston chamber, whereby high pressure and low pressure cylinders are formed, a receiver adapted to receive the expanded fluid from the high pressure cylinder and 105 retain it for use when required in the low pressure cylinder, and a single controlling valve for said cylinders and receiver.

54. In a compound pneumatic hammer, a barrel having its forward end open for the 110 shank of the working tool and provided with a differential piston chamber, whereby high pressure and low pressure cylinders are formed, a receiver adapted to receive the expanded fluid from the high pressure cylinder and 115 retain it for use when required in a low pressure cylinder, a single controlling valve, ports and passages common to said valve, receiver and piston chamber, and means for causing live air pressure to constantly act upon a portion of said valve to shift the same. 120

55. In a compound pneumatic hammer, a barrel having its forward end open to receive the shank of the working tool and 125 having a differential piston chamber therein, a differential plunger located in said piston chamber and having pistons therein of different diameters, a receiver, a single valve for controlling the inlet and exhaust 130

of motive fluid to and from said piston chamber, and means for causing live motive fluid to act constantly upon an end of said valve for shifting the same.

- 5 56. In a compound pneumatic hammer, a barrel having its forward end open for the reception of the shank of a working tool, said cylinder having therein a differential piston chamber, a differential plunger located in said piston chamber, a single valve for controlling the reciprocations of said plunger, means for causing live motive fluid to act constantly upon an end of said valve, a receiver, and connections common to said 10 receiver, piston chamber and said valve, whereby motive fluid is admitted from said receiver to act expansively upon a low pressure area of said plunger simultaneously with the admission of live motive fluid to 15 the high pressure area of said plunger to augment the momentum of the striking blow of said plunger.

57. In a compound pneumatic impact tool, a barrel having its forward end open to receive the shank of the working tool, a plurality of working cylinder portions of different diameters, a working plunger having 20 pistons of different diameters reciprocable

in said cylinder portions, a single valve for admitting motive fluid to a small diameter 30 cylinder portion, a plurality of receivers connected together, and means controlled by said piston for admitting expanded motive fluid from one of said cylinders to such receivers, said single valve admitting expanded 35 motive fluid from said receivers to the cylinder portion of larger diameter to augment the blow of the piston.

58. In a compound pneumatic impact tool, a grasping handle having a pressure supply 40 duct therethrough, means for manually controlling said duct, a valve chamber carried by said handle and adapted to receive a single valve therein, a closure for said valve chamber, a plunger chamber in said closure, 45 and a constantly open passage leading from said pressure supply duct to said plunger chamber, in combination with a barrel, a hammering piston therein, a receiver in said barrel, and passages common to said barrel, 50 receiver and valve chamber.
